W. R. HOFFMANN

PIPE SUPPORTING ATTACHMENT

Filed April 9, 1925

UNITED STATES PATENT OFFICE.

WILLIAM R. HOFFMANN, OF OREGON, MISSOURI.

PIPE-SUPPORTING ATTACHMENT.

Application filed April 9, 1925. Serial No. 21,904.

To all whom it may concern:

Be it known that I, WILLIAM R. HOFFMANN, a citizen of the United States, residing at Oregon, in the county of Holt and State of Missouri, have invented certain new and useful Improvements in Pipe-Supporting Attachments, of which the following is a specification, reference being had to the accompanying drawings.

This invention relates to devices for supporting pipes, and the object of the invention is to provide a very simple and inexpensive attachment adapted to be applied to any ordinary form of smoking pipe to prevent the pipe, when not in use and placed on a flat surface, from falling or tipping over and thus spilling the tobacco or ashes on the table or burning up the table cover.

A further and more specific object is to provide a device of this character which is resiliently contractible about the stem or a portion of the bowl of the pipe and which will permit the device to be used with pipes having larger or smaller stems or bits.

A still further object is to provide a device of this character which consists of a band of resilient metal preferably coiled to a greater or less extent so as to embrace the stem of the pipe, and so formed as to provide a flat base upon which the pipe will rest and be supported from any tipping movement.

My invention is illustrated in the accompanying drawing, wherein:—

Figure 1 is an elevation of a pipe having a holder applied to the stem thereof in accordance with my invention;

Figure 2 is a perspective view of one form of the holder;

Figure 3 is a perspective view of a modified form of the holder shown in Figure 2;

Figure 4 is a perspective view of another modification of the holder;

Figure 5 is a perspective view of a modified form of the construction shown in Figures 2 and 3;

Figure 6 shows a holder applied to a straight pipe.

Referring to the drawings, it will be seen that I have illustrated a pipe support composed of a strip of resilient sheet metal which is bent so as to form a base and a portion embracing or surrounding the stem of the pipe or the bit thereof. In Figure 2, the device comprises a strip 10 which at one end is formed to provide a flat portion 11

adapted to rest flat upon a table or other support. At the extremity of this flat portion the metal strip is re-bent, as at 12, and extends preferably for a distance parallel to the portion 11, as at 13, and then is curved around, as at 14, to form a circular band, the free end of which approximates the upper face of the portion 13, this free end preferably being formed in a bit 15 extending beyond the body of the strip so as to form a means whereby the strip may be readily opened.

In a device of this character, the body 14 is contractible and expandible and as a consequence may be bent to receive the stem or bit of a pipe and then the resilience of the material will cause it to close and grip the pipe stem. Under these circumstances the device will act to support the pipe from any tipping movement by means of the base 11.

In Figure 3, I illustrate another form which is of exactly the same principle as the first named form except that the body 14 instead of being formed as a simple circle is carried around one or more times in a spiral manner.

In this figure, 10^a designates the strip, 11^a the base, 12^a the fold, 13^a the flat portion overlying the base, 14^a the body, this body being formed by bending the strip around so as to form an outer band, and an inner spiral continuation 16, this spiral continuation at its free extremity being formed with 15^a a transverse bead in the manner heretofore described. In this form of the device, the body may be opened up so as to permit the ready insertion of the bit or stem of a pipe and when released the body will resiliently close upon the pipe, thus holding the support or foot in position upon the pipe.

In Figure 4, I illustrate another form which is preferably made of wire, though it might be made of a strip of resilient material, and the wire is bent so as to provide a pipe stem embracing portion 17, the ends of the wire crossing each other so as to provide two laterally extending portions 18 which constitute a base. In this construction also it will be seen that I have provided a resiliently contractible and expandible pipe stem embracing portion and a base from which the pipe stem embracing portion rises. This device is adapted to be applied to any size pipe and either upon the bit thereof or that portion of the stem extending

from the bowl and will support the pipe from tipping.

Obviously these devices may have an ornamental character and be made of a large variety of different materials. Obviously also slight modifications might be made without departing from the spirit of the invention. Thus, for instance, in Figure 5 I have illustrated the construction shown in Figure 2 but without the transverse bead 15. Inasmuch as the construction in Figure 5 is the same as that in Figure 2, the same reference numerals have been used, and while I have shown in Figure 1 this device applied to a curved pipe, in Figure 6 I have illustrated it as applied to a straight pipe.

I claim:—

1. A pipe support of the character described comprising a strip of resilient material bent to form a flat base, and a resiliently contractible pipe stem embracing ring disposed in the same plane with the base, the base extending transversely of the axis of the ring.
2. A pipe support of the character described comprising a strip of resilient mate-

rial bent to form a flat base, the material then being re-entrantly bent upon the flat base and extended to form a resiliently contractible pipe stem embracing portion.

3. A pipe support of the character described comprising a strip of resilient metal bent to form a flat base, then re-entrantly bent upon the flat base and curved to form a resiliently contractible pipe stem embracing portion, the free end of the pipe stem embracing portion being extended spirally and formed at its extremity with a transversely extending bead projecting beyond the strip whereby the stem embracing portion of the strip may be expanded.

4. A holder for pipes formed of a narrow strip of relatively thin resilient material bent to provide a base and then bent spirally to form a resiliently contractible pipe stem embracing portion, the free end of the strip being formed to provide a bead, the bead extending transversely beyond the side edges of the body of the strip.

In testimony whereof I hereunto affix my signature.

WILLIAM R. HOFFMANN.
